Specification for Design.

Patented Nov. 23, 1915.

Application filed February 25, 1915. Serial No. 10,642. Term of patent 14 years.

To all whom it may concern:

Be it known that I, ALEXANDER L. Fox, a citizen of the United States, residing at East St. Louis, in the county of St. Clair and State of Illinois, have invented a new, original, and ornamental Design for an Insulator-Body for Trolley-Wire Hangers, of which the following is a specification, reference being had to the accompanying drawing, forming a part thereof.

The drawing illustrates an insulator body for a trolley wire hanger, showing my new design, in which drawing—

Figure 1 is a view of the upper end of

the insulator body. Fig. 2 is a side elevation, and Fig. 3 is a view of the lower end.

I claim:

The ornamental design for an insulator body for a trolley wire hanger, as shown.

In testimony whereof, I have signed this specification in the presence of two subscribing witnesses, this 23rd day of February, 1915.

ALEXANDER LEE FOX.
